[57] CLAIM

The ornamental design for a chair base, as shown and
described.

DESCRIPTION

FIG. 1 is a perspective view of a chair base showing my
new design;

FIG. 2 is a front elevational view thereof;

FIG. 3 is a side elevational view, the opposite side being
a mirror image thereof;

FIG. 4 is a top plan view thereof; and

FIG. 5 is a rear elevational view thereof.

In order to illustrate the environment in which the
claimed design is used, exemplary wheels are shown in
phantom. The wheels form no part of the claimed de-
sign.
